(57) CLAIM

The ornamental design for a display screen or portion thereof with icon, as shown and described.

DESCRIPTION

The file of this patent contains at least one drawing/photograph executed in color. Copies of this patent with color drawings/photograph(s) will be provided by the Office upon request and payment of the necessary fee.

The sole FIGURE shows a display screen or portion thereof with icon showing our new design.

The peripheral dashed broken lines that surround the icon represent a display screen or portion thereof; the peripheral dashed broken lines form no part of the claimed design.
